UNITED STATES PATENT OFFICE.

CHARLES H. T. PETERS, OF BALTIMORE, MARYLAND.

DESIGN FOR A DELIVERY-WAGON BODY.

No. 38,009.

Specification for Design.

Patented May 8, 1906.

Application filed January 10, 1906. Serial No. 295,506. Term of patent 14 years.

To all whom it may concern:

Be it known that I, CHARLES H. T. PETERS, a citizen of the United States, residing at Baltimore, in the State of Maryland, have invented a new, original, and ornamental Design for Delivery-Wagon Bodies, of which the following is a specification, reference being had to the accompanying drawing, forming part thereof.

The figure is a perspective front end view

of the delivery-wagon body, showing my new design.

I claim—

The ornamental design for a delivery-wagon body, as shown.

CHARLES H. T. PETERS.
